(57) CLAIM

I claim the ornamental design for an adjustable rope cleat hook, as shown and described.

DESCRIPTION

FIG. 1 is a perspective view showing a side and rear view of the adjustable rope cleat hook of my design;

FIG. 2 is a perspective view showing the opposite identical side thereof;

FIG. 3 is a front view of the adjustable rope cleat hook of my design.

FIG. 4 is a rear view thereof;

FIG. 5 is a top view thereof; and,

FIG. 6 is a bottom view thereof.
